(57) **CLAIM**

The ornamental design for a charging case for smart ring, as shown and described.

DESCRIPTION

FIG. 1 is a top, front, left side perspective view of a charging case for smart ring, showing our new design;

FIG. 2 is a bottom, rear, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front, right side perspective view of the charging case for smart ring in an open configuration.

The broken lines in the drawings depict portions of the charging case for smart ring that form no part of the claimed design.
